UNITED STATES PATENT OFFICE.

HERBERT R. BLISS, OF NIAGARA FALLS, NEW YORK.

SHIPPING CASE.

Application filed December 6, 1922. Serial No. 605,302.

To all whom it may concern:

Be it known that I, HERBERT R. BLISS, a citizen of the United States, residing at Niagara Falls, in the county of Niagara 5 and State of New York, have invented certain new and useful Improvements in Shipping Cases, of which the following is a specification.

This invention relates to a method of sealing fibre shipping cases and has for its object a method of wire-stitching the flaps together so as to form a very strong closure that may be expeditiously sealed.

In the drawings:

Fig. 1 is a perspective of the case packed and sealed.

Fig. 2 is a perspective of the case before it is packed and sealed.

Fig. 3 is a cross section of the case taken 20 on the line 3-3 of Fig. 1.

Fig. 4 is a plan view of the case showing how it is sealed.

Fig. 5 is a cross section fragmentary in character and similar to the one shown in 25 Fig. 3, showing the position of the anvil when taking stitches 14 to 18 inclusive.

Fig. 6 is a fragmentary cross section showing the position of the anvil when taking 30 stitches 1 to 8 inclusive.

Fig. 7 is a fragmentary section showing how stitches 9 to 13 inclusive are taken.

Figs. 8 to 10 show the blanks.

The body of the box and the closure together are constructed out of three separate blanks, a body blank which forms the side walls *a*, the bottom wall *b* and the cover wings *c* and *d* the end blanks are designated *e* and *f* and one has a cover wing *e'* and the other *f'*. The fastening strips are 35 designated *h* and are preferably put on the end blanks although they can be placed on the body blank. The fastening strips are 40 folded right angularly and form the vertical corners and the two bottom corners 45 when they are stitched to the adjoining wall.

The cover wing *e'* is turned in and forms the underlying cover wing. The two cover wings *c* and *d* then become the intermediate 50 set as they are turned in over the cover wing *e'*.

Referring to Fig. 4, the character of the closure and the method of taking the 55 stitches is indicated. Also referring to Fig. 6 it will be seen that the cover wing *f'* is turned back and the anvil *g* is inserted

under the cover wing *e'* and also of course under the cover wings *d* and *c*. The stitches 1 to 8 inclusive may be taken in the order indicated or in a somewhat different order. The anvil is then withdrawn and inserted as shown in position 2 Fig. 4, that is, over the intermediate cover wing *d* and under the intermediate cover wing *c* and the cover wing *f'*. The stitches 9 to 13 inclusive may then be taken in the order indicated or in a varying order. The anvil is then taken out and inserted in the position shown at 3 Fig. 4 and the stitches 14 to 18 inclusive taken. In this position the anvil is under the wing *d* and the superimposed wing *f'*. The stitches 14 to 18 taken may be taken in the order indicated or in a varying order. Obviously the number of stitches taken may be varied more or less.

We have spoken of the anvil as being inserted in and placed in the various positions. In actual practice the anvil would be a stationary one and the box would be 80 swung around on the table to insert the anvil in the various positions.

I claim:

1. The method of sealing a shipping case provided with two pairs of cover wings at the end to be sealed, which comprises the folding in of one cover wing, to become the lower wing, then the folding in of the pair of cover wings at right angles to the lower wing to become intermediate cover wings, then the insertion of a blade anvil under the cover wings at the end of the case opposite the lower cover wing, and the stitching of the intermediate cover wings along their meeting edges to the lower cover wing, then the withdrawal of the anvil and the folding of the remaining cover wing to become the upper cover wing, then the insertion of the blade anvil in at one end of the upper cover wing over the underlying intermediate cover wing and under the other intermediate cover wing, the stitching of such other intermediate cover wing to the upper cover wing, the withdrawal of the anvil and then the insertion of the anvil over the lower cover wing and under the intermediate cover wing, and the stitching of the upper cover wing to the intermediate cover wing to which it has not yet been stitched.
2. The method of sealing a shipping case provided with two pairs of cover wings at the end to be sealed, which comprises the

folding in of one of the cover wings to form the lower cover wing, the folding in of the two opposite cover wings at right angles to the same forming intermediate cover wings, the insertion of a blade anvil under the intermediate cover wings and the lower cover wing, at the end of the case opposite the lower cover wing and the driving of fasteners along the meeting edges of the intermediate cover wings and along one end edge of one intermediate cover wing to fasten the same to the lower cover wing, the withdrawal of the anvil and the folding over of the remaining cover wing to form the upper cover wing, the insertion of the anvil in at one end of such upper cover wing and over the intermediate cover wing and under the opposite intermediate cover wing, the driving of metallic fasteners through the upper cover wing and the underlying intermediate cover wing along one half of the free edge of the upper cover wing and along the end thereof, the withdrawal of the anvil, and finally the insertion of the anvil under the intermediate cover wing which has not yet been stitched and over the lower cover wing, and driving

metallic fasteners along the other half of the free edge of the upper cover wing and along the other end edge.

3. The method of sealing a fiber shipping case provided with two pairs of cover wings which comprises the turning in of one cover wing, the folding over of the pair of cover wings located at right angles to the first mentioned cover wing, the insertion of a blade anvil in under said pair of cover wings, and under the first turned in cover wing, the driving of metallic fasteners through the said pair of cover wings, and the first turned in cover wings but leaving a space for the insertion of the anvil, the withdrawal of the anvil and the insertion of the same in at the opposite end of the case through the space left therefor and the turning of the remaining flap down over the intermediate pair of cover wings and the driving of metallic fasteners through such last down cover wing and intermediate cover wings and the withdrawal of the anvil.

In testimony whereof I affix my signature.

HERBERT R. BLISS.
